COMBINED TOOL HOLDER AND CHIP BREAKER

Robert D. Shaw, Hartford, Conn., assignor, by
mesne assignments, to Niles-Bement-Pond
Company, New York, N. Y., a corporation of
New Jersey

Application July 22, 1935, Serial No. 32,496

1 Claim. (Cl. 29—96)

This invention relates to a combined tool holder and chip breaker particularly adapted to be mounted on the tool slides of lathes, planers and similar machine tools.

5 An object of the present invention is to provide an improved holder for a small tool bit suitably housed within a body member and adapted to be readily mounted within the ordinary tool post of a lathe, planer or the like, there being mounted 10 in the holder a bar adjacent the tool and in the path of the chips or cuttings of the tool.

Another object of the invention is to provide closely adjacent the cutting edge of the tool an abutment acting as a breaker or deflector for 15 the cuttings or chips so that chips as they are formed by the cutting tool may be curled sufficiently immediately after leaving the cutting edge that they will be broken up or deflected away from the work.

20 Another object of the invention is to mount this chip breaking means directly above the cutting surface of the tool over which the chip passes, the breaker being adjustable to several positions relative to the cutting edge so that for different 25 depths of cut or classes of work being operated on the breaker may be laterally positioned relative to the cutting edge to obtain the necessary breaking up or deflection of the chips or cuttings with a minimum of power absorption.

30 With the above and other objects in view my invention consists in the features of construction and operation set forth in the following specification and illustrated in the accompanying drawing.

In the accompanying drawing annexed hereto 35 and forming a part of this specification I have shown my invention embodied in a two-part tool holder for lathes or planers within which is adjustably and removably mounted a cutting tool preferably of special tungsten carbide or other 40 selected high speed cutting steel removably mounted in the holder. It will be understood, however, that the invention can be otherwise embodied and that the drawing is not to be construed as defining or limiting the scope of the 45 invention, the claim appended to this specification being relied upon for that purpose.

In the drawing:

Figure 1 is a plan view of a complete holder 50 showing the inserted cutting tool and the chip breaking or deflecting member in proper adjusted operative position.

Fig. 2 is a complete side elevation of the tool holder, parts being broke away to more clearly 55 show the construction.

Fig. 3 is an end elevation of the complete tool and chip breaking member; and

Fig. 4 is a transverse section of the holder taken upon the plane of line 4—4 of Fig. 2.

In the above mentioned drawing I have shown 5 but one embodiment of the invention which is now deemed preferable but it is to be understood that changes and modifications may be made within the scope of the appended claim without departing from the spirit of the invention. 10

Briefly and in its preferred aspect, my invention may include the following principal parts: First, a tool holder formed of two members one above the other and adapted to enclose a cutting tool therebetween partially within both of these 15 members; second, adjusting means for positioning the cutting tool generally longitudinally within the holder; third, a bar retained within the upper of the two tool holder members disposed parallelly to the tool and resting against the 20 upper or cutting surface of the tool but spaced a short distance laterally from the cutting edge; and fourth, adjusting means for the bar, the bar being clamped with the tool when the holder is 25 in operative position.

Referring more in detail to the figures of the drawing, I provide a tool holder formed by a lower member 10 and an upper member 11. These two members when assembled provide a tool holder of conventional length and cross section for mounting within the tool post of a lathe 30 cross slide, planer tool head or the like. As shown most clearly in Fig. 2, these members 10 and 11 are fitted together along an oblique plane surface and are retained in proper relative longitudinal 35 position by a transverse key 12 entering aligned slots within the lower and upper members 10 and 11. Preferably the key 12 may be suitably secured within the slot in the lower member 10 and loosely or slidably mounted within the slot in 40 the upper member 11 enabling the members of the tool holder to be readily separated and returned to proper relative positions.

Within the lower member 10 is a recess or slot 13 extending parallelly with the upper or oblique 45 surface of the lower member and adapted to accommodate a cutting tool or bit 14 inserted therein. The tool 14 may extend somewhat beyond the end of the tool holder and has its extended end, formed in any preferred manner as 50 by grinding to provide any preferred form of cutting surfaces. As shown in Fig. 3, the slot 13 within member 10 is disposed obliquely laterally of the holder to give the upper surface of the cutting tool 14 the necessary rake. The end of 55

the member 18 adjacent the cutting tool may be extended forwardly directly below the tool to form a support therefor.

In order to adjustably position the cutting tool 14 longitudinally of the holder as it becomes worn, there is provided a screw 15 threaded into the member 18 in a direction substantially parallel to the slot 17. By means of this screw 15 the cutting tool 14 may be readily adjusted forwardly 10 to the proper position relative to the cutting end of the tool holder and always supported against movement away from the work.

As the cutting tool 14 is disposed obliquely in a vertical plane and tilted laterally as viewed 15 from the left end of the tool holder as shown in Figs. 1 and 2, a small portion of the cutting tool throughout its length extends into the upper member 11 which is suitably recessed as shown at 16 to accommodate this portion of the tool. Laterally adjacent this slot 16 formed in the upper member 11 is a slot 17 within which is adjustably 20 fitted a bar or rod 18 preferably square in cross section and extending parallelly with and resting on the upper surface of the cutting tool 14. This bar or rod 18 rests throughout its length 25 upon a portion of the upper surface of the cutting tool 14 and extends forwardly to closely adjacent the cutting edge longitudinally of this cutter. This bar 18 is set a short distance laterally back 30 or at the side of the cutting edge of the tool, this distance being adjustable within certain limits by means of shims 19 placed within the slot 17 closely adjacent the bar 18. The slot 17 in the upper member is of greater width than the bar 18 35 and several shims 19 may be used to take up the extra width of this slot. By arranging the shims 19 on one side or the other or partially on either side of the bar 18 the distance of the bar 18 laterally from the cutting edge of the tool 14 may 40 be adjusted to three or more positions. Also when the upper member 11 is clamped against the lower member 10 within the tool post of a lathe or other machine tool the cutting tool 14 and bar 18 forming the chip breaking member will be 45 rigidly positioned and retained against movement or vibration in any direction within the holder.

In using the tool holder the bar 18 forming the chip breaker is adjusted forwardly so that its end is substantially in alignment with the end of the cutting surfaces of the tool 14 and is of sufficient 50

height above and extends at right angles to the upper surface of the tool 14 so that a chip as it passes over the upper surface of the cutting tool will strike against the side wall of this bar 18 and be deflected sharply upward. As the metal chips immediately upon leaving the cutting edges of the tool 14 are extremely hot and therefore easily bent and twisted the chips are coiled upon a small enough circle to effect a breaking up of the chips and preventing an extremely long chip becoming wrapped around the work. The effect of the bar 18 is to deflect the chip directly away from the work being operated on and upon being broken up may drop directly into the chip receptacle and not allowed to entangle itself about the work being operated on. To retain the cutting tool 14 and bar 18 securely in place it is only necessary to clamp the members 10 and 11 together as is done when they are mounted in operative position in a machine tool. Clamping 20 members 10 and 11 together forces the rod or bar 18 in its recess 17 downward against the upper surface of cutting tool 14. Cutting tool 14 is therefore forced against the lower surface of its recess in member 10. By the positioning of one 25 or more of the shims 19 in front or in back of the bar 18 the distance laterally from the cutting edge of the tool 14 to the bar 18 may be widely varied. By means of this variation the amount 30 of curl given the chip as it is formed and leaves the cutting edge is regulated to the amount necessary to prevent the chip becoming wrapped around the work and if desired to break up the chip into relatively short lengths.

What I claim is:

A combined tool holder and chip breaker comprising in combination, a body portion, a cutting tool adjustable therein, a bar extending upward at a right angle from the cutting surface of said tool and disposed substantially parallel to said cutting edge, shims disposable on either side of said bar to adjustably position said bar laterally of said cutting edge, whereby cuttings removed by said tool will strike against a side face of said bar at predetermined adjustable distances therefrom and be deflected upward thereby, and means retaining said cutting tool and bar in adjusted positions when said holder is in operative position.

ROBERT D. SHAW.
